UNITED STATES PATENT OFFICE.

ARTHUR R. WILLFORD, OF MINNEAPOLIS, MINNESOTA, ASSIGNOR TO THE ELECTRIC OZONE COMPANY, OF MINNEAPOLIS, MINNESOTA, A CORPORATION OF MINNESOTA.

PROCESS OF WASHING AND DRYING CLOTHES.

1,362,658.

Specification of Letters Patent. Patented Dec. 21, 1920.

Application filed March 8, 1917. Serial No. 153,453.

To all whom it may concern:

Be it known that I, ARTHUR R. WILLFORD, citizen of the United States, resident of Minneapolis, in the county of Hennepin and State of Minnesota, have invented certain new and useful Improvements in Processes of Washing and Drying Clothes, of which the following is a specification.

This invention relates to improvements in the process of washing and drying clothes in laundries which consists in the regulated application of ozone both in the washing and drying operations.

The invention relates further to improvements in apparatus for applying the ozone in the washing and drying operation.

The invention consists generally in the method and in the construction and arrangement of the apparatus hereinafter described and particularly pointed out in the claims.

The accompanying drawing is a plan view, partly in section, of an apparatus embodying my invention and constructed to carry out my process.

In the accompanying drawing 2, 2 represent ozone generators, wherein ozone may be generated by the application of an electric current, changing the oxygen of the air into ozone. 3, 3 represent washing machines of any preferred construction. 4 represents an extractor or centrifugal drier, 5 represents a shaker or tumbler, 6 a mangle and 7 an air pump or pressure blower. 8 represents a fan or volume blower, 9 a shaker or tumbler and 10 an inclosed drying-room.

The pressure blower 7 is connected with one of the ozone generators by a suitable pipe 11, and a pipe 12 with suitable branches, 40 each provided with a valve 13, leads to the washing machine 3, the extractor 4, shaker 5, and mangle 6. The fan blower 8 is connected to the other generator by a pipe 15, and a suitable pipe 16 leads from the fan blower and is connected by branch pipes 17 and 18, having controlling valves 19 and 20, with the tumbler 9 and the drying room 10. I also prefer to provide an exhaust pipe 21 having branches 22 arranged within the 50 drying-room 10 whereby the surplus air and ozone and the moisture carried thereby may be drawn out of the drying-room 10.

In the washing machines the ozone is forced under pressure into and distributed

through the wash-water, whereby as the 55 clothes are washed the ozone is directly applied to all portions thereof. In the extractor the ozone is distributed thoroughly through the clothes and permeates the entire body thereof, being carried along by the 60 centrifugal action of the water that is taken from the clothes. In the mangle the ozone is applied directly to the clothes as they are passed through the rolls, and in the shaker the ozone is also distributed through 65 the body of clothes.

It is especially essential in applying the ozone to the washing machines and the extractor that it be forced through the water and the clothes by pressure, and for this 70 purpose I employ the air pump or pressure blower 7 which enables me to get any desired pressure on the ozone as it is forced into these machines. In applying the ozone to the tumbler 9 and the drying-room 10 75 it is important to provide a large volume of ozone which may be applied under a low pressure, and retained in the inclosure any desired length of time. For this reason I employ in connection with these portions of 80 the apparatus the fan or volume blower 8.

With this process I eliminate the use of chemical bleaches and reduce the soap consumption fully 50% by the action of the ozone applied in the wash-water and I also 85 reduce the time of washing and rinsing fully 50%.

From the washing machines the clothes are transferred to the extractor, where the ozone is applied continuously while the 90 water is being extracted. From the extractor the clothes are passed to the shaker 5, which is of an inclosed type and in which all portions of the clothes are subjected to the ozone and in which they are allowed to 95 remain for a considerable period of time.

At the mangle the ozone is blown directly on the clothing so that it will be thoroughly saturated with ozone as it passes to the hot roll. The clothes then come out with a 100 natural bleach, thoroughly sterilized and with a sweet, fresh odor.

In the tumbler 9 and drying-room 10 the clothes are again thoroughly subjected to the ozone, which gives a natural bleach and de- 105 stroys all soap and laundry odors. In the tumbler and dry rooms the usual amount of heat employed for drying the clothes may

be lessened as in the ozonized atmosphere provided the clothes will dry much faster than in the natural air.

By using this process I increase the life 5 of clothes considerably by eliminating the usual chemical bleach and reducing the time the clothes remain in the water. The clothes are kept white with a natural bleach and free from any laundry odors and will be as 10 fresh as when dried in the open air.

I do not limit myself to the details of the construction herein illustrated and described as the same may be varied in many particulars without departing from my invention.

15 I claim as my invention:

1. The improvement in the art of washing and drying clothes, which consists in forcing ozone into contact with and through the body of clothes in each step of the washing 20 and drying operation.

2. The improvement in the art of drying clothes which consists in submitting the wet clothes, after removal from the washing apparatus to the action of a centrifugal extractor, and simultaneously forcing ozone 25 into and against the body of clothes and causing it to be carried through the clothes by the centrifugal action of the water.

3. The improvement in the art of washing and drying clothes which consists in forcing 30 ozone through the body of the clothes in the washing operation, in the centrifugal water extracting operation, in the mangling operation and in the tumbling and shaking operations, and finally completing the operation 35 in a drying room containing an atmosphere of ozone, substantially as described.

In witness whereof I have hereunto set my hand this 24th day of February, 1917.

ARTHUR R. WILLFORD
